COIN CONTROLLED MECHANISM

Walter Van Guilder, Oak Park, and Karl H. Sommermeyer, Evanston, Ill., assignors to G-M Laboratories, Inc., Chicago, Ill., a corporation of Illinois

Application March 9, 1936, Serial No. 67,842

8 Claims. (Cl. 194—55)

Our present invention relates generally to mechanism for detecting coins and the like for controlling the operation of other apparatus according to the presence or absence of coins.

5 Coin detecting mechanisms are widely used in vending and amusement machines and the like which are adapted to operate only when coins are inserted therein.

The objects of the present invention include 10 the provision of a new and simplified mechanism for detecting coins and for controlling the operation of other apparatus in accordance with the presence or absence of coins. The objects also include the provision of a simple but rugged 15 mechanism of the type indicated which may be manufactured at a low cost.

The coin apparatus of our present invention is adapted to be employed in an amusement and/or vending machine such as that shown and described in the co-pending application of Archie J. McMaster, Ser. No. 64,235, filed Feb. 17, 1936. It is further adapted to be employed with the mechanisms for operating amusement devices which are shown and described in the co-pending 20 application of Walter Van Guilder, Serial No. 62,164, filed February 3, 1936, and the application of Karl H. Sommermeyer, Serial No. 62,165, filed February 3, 1936.

These and other objects and advantages of our 25 present invention will become apparent as the description proceeds.

In order better to acquaint those skilled in the art with the teachings and practice of our present invention, we now shall describe a specific embodiment thereof, reference being had to the accompanying drawings which form a part of this specification and in which:

Fig. 1 is a general view in perspective of the 30 interior mechanism of an amusement machine embodying our present invention.

Fig. 2 is an elevational sectional view of a part 35 of the apparatus of Fig. 1 looking towards the right in Fig. 1.

Fig. 3 is a sectional elevation through the coin 40 mechanism of the apparatus of Fig. 1. It is taken looking towards the left in Fig. 1, and is a section taken along the line 3—3 of Fig. 6.

Fig. 4 is another section similar to the section 45 of Fig. 3 but taken so as to show a different part of the apparatus. It is taken along the line 50 4—4 of Fig. 7.

Fig. 5 is a view like Fig. 4, but showing the apparatus in a different operated position.

Fig. 6 is a section taken along the line 6—6 of 55 Fig. 3 and showing the apparatus in the same

operated position as that in which it is shown in Fig. 3.

Fig. 7 is a section taken along the line 7—7 of Fig. 4.

Fig. 8 is a section taken along the line 8—8 of Fig. 6.

Referring particularly to Fig. 2, and, also, to Fig. 1, a wheel 10 is adapted to be spun and brought to a random but registered stop so as to bring one of a series of characters which constitute a design on the periphery of the wheel 10 into register with an index (not shown), located in a viewing aperture 12 (shown in dotted lines), in a panel 14. The mechanism for driving and stopping the wheel 10 is more completely shown and described in the co-pending applications of Walter Van Guilder and Karl H. Sommermeyer already referred to.

The entire mechanism is mounted on an end plate 16 shown in Fig. 1 and the panel 14 which is secured thereto. The end plate 16 constitutes part of an enclosing case which is indicated generally by the reference numeral 35. A shaft 21, journaled in the end plate 16, is adapted to be rotated in a counter-clockwise direction as viewed in Fig. 2 by means of a handle (not shown), on the outside of the end plate 16, that is, to the left of the plate 16 as viewed in Fig. 1. The shaft 21 carries a crank arm 22 which in turn carries a spreader 23 which is pivoted thereto by means of a pin 24. The wheel 10 is carried on a shaft 26 and its driving mechanism includes an over-running clutch indicated by the reference numeral 27 (not fully shown). The driving member of the over-running clutch includes the arm 28 which has a spreader 29 pivoted thereto at a pin 30. The head of the pin 30 strikes against a pair of bosses 33 and 34 located on the end plate 16 to act as stops for the arm 28.

The crank arm 22 in the position shown in Fig. 40 2 stops against the hub of the arm 28 and in another position thereof stops against the enclosing case 35. A pair of springs 37 and 38 are tensioned by the spreaders 23 and 29. The points of fastening of the springs 37 and 38 to the 45 spreader 23 do not lie on a line which passes through the center of the pin 24 but rather lies on a line which passes between the pin 24 and the pin 30. Similarly, the points of fastening of these same springs to the spreader 29 lie on a line 50 which, also, passes between the centers of the pins 24 and 30. The use of the two springs 37 and 38 and the particular arrangement of their points of fastening to the spreaders 23 and 29, accomplishes two things: First, it permits the 55

line of action of the springs, which line passes through the centers of the pins 24 and 30, to cross the axis of the shaft 26 without requiring that that shaft be interrupted to permit a spring to 5 pass therethrough; and second, it causes the spreaders 23 and 29 to always tend to assume positions which are substantially perpendicular to the line of action of the springs between the pins 24 and 30. The two spreaders 23 and 29 and the 10 springs 37 and 38 constitute a spring assembly or spring means acting between the pins 24 and 30. Therefore, pins 24 and 30 constitute spring fastening points of the arms 22 and 28.

The upper end of the spreader 29 has a notch 15 39 which normally engages a latch piece 41 which serves to prevent actuation of the wheel 10 in a manner which will be described presently. The two arms 22 and 28 together with the springs 37 20 and 38, the spreaders 23 and 29 and the various stops for the two arms, constitute a snap mechanism which in turn constitutes part of the driving mechanism for the wheel 10. The arm 22 is the actuator arm of the snap mechanism and the arm 28 is the follower arm thereof.

25 Assuming that the latch piece 41 is in such a position that it does not engage the notch 39 of the spreader 29, the wheel 10 may be set into motion as follows:

Then the shaft 21 is rotated in the counter-clockwise direction as viewed in Fig. 2 by means of the handle already mentioned, the arm 23 carries the pin 24 down until the line between the centers of the pins 24 and 30 crosses the axis of the shaft 26. Thereupon the arm 23 rotates with 30 a snap action in a clockwise direction as viewed in Fig. 2 until it stops against the boss 33. This rotates the driving member of the over-running clutch 27 in that direction in which it drives the wheel 10. When the arm 28 stops against the 35 boss 30, the clutch 27 disengages the wheel 10 so that the wheel spins freely. The wheel subsequently and independently of any further operation of the arms 22 and 28, comes to a registered stop. The mechanism for bringing this 40 wheel to a stop is more fully described in my co-pending application already referred to. It comprises a pair of centrifugal weights 43 and 44 shown in Figure 1 which carry a dog into and out of engagement with the notches of a wheel 45. 45 The wheel 45 is fixed to the shaft 26 so as to be stationary. The notches of the wheel 45 provide a plurality of registered portions and the centrifugal weights and the dog operated thereby are adapted to stop the wheel in one of these 50 positions selected at random and to register it in that position.

The operation of the arms 22 and 28 which set the wheel 10 into rotation has not permitted the line of action of the springs 37 and 38 to cross the 55 axis of the shaft 21. Consequently, the springs 37 and 38 still tend to rotate the arm 22 in a clockwise direction as viewed in Fig. 2 about its shaft 21. Therefore, the release of the handle permits the arm 22 to return to the position in which it is shown in Fig. 2 so as to cause the line of action between the pins 24 and 30 again to cross the axis of the shaft 26 so that the arm 28 snaps back to its normal position in which it is shown in Fig. 2 where it stops against the boss 34. The return motion of the arm 28 does not 60 drive the wheel 10.

The inclosing case 35 carries a casting 51 (shown in Figs. 2, 3, 6, and 7), having a hollow 65 therein which is adapted to receive a coin or the like. An opening in the bottom of the casting 70

51 is adapted to permit the coin to fall therefrom through another opening 52 in the panel 14 so that it enters a channel formed by the panel 14 and a channel piece 55. Referring to Figs. 3, 5, 6, 7, and 8, the channel just referred to contains 5 a pair of slides 57 and 58 which are adapted to handle and detect the coin. The slide 57 carries a pin 61 which extends through an opening in the channel piece 55. This pin 61 engages a slotted lever 62 (seen in Fig. 1), and is held by a spring 63 in a normal position at the extreme right of its travel as viewed in Fig. 1 and at the extreme left of its travel as viewed in Figs. 6 and 7. The slide 57 as it is seen in Fig. 6 carries at its extreme left end, a projection 65 on the front surface thereof 15 which is adapted when the slide 57 moves to the right, to sweep through the space into which the coin falls from the aperture 52. The slide 58 is located forward of the slide 57 as viewed in Fig. 6 so as to be in alignment with the projection 65 of the slide 57 and in alignment with the coin. The end of the slide 58 is cut off at an angle so as to adapt it to engage a coin in the channel and direct the same downward.

The slide 58 is off-set at 68 at its extreme right 20 end as best may be seen in Fig. 8. The off-set portion 68 engages the end of the channel piece 55 to act as a stop to limit the motion of the slide 58 toward the left as seen in Fig. 8 and, also, engages a spring 69 which holds the slide 58 in its 25 normal position at the extreme left of its travel as viewed in Figs. 6, 7, and 8. This off-set portion of the slide 58, also, carries the latch piece 41 already mentioned in connection with the description of the snap mechanism for driving the 30 wheel 10. The operation of this latch will be described presently.

In the bottom of the channel piece 55 and off-set therein to the right of the aperture 52 as seen in Figs. 6 and 7 is another aperture opening into 40 a coin trap 71 which depends from the channel containing the slides 57 and 58. The dimensions of the slides 57 and 58 and the positions of their stops are so arranged that if a coin is in position between the projection 65 of the slide 57 and the 45 end of the slide 58, the motion of the slide 57 towards the right (Figs. 6, 7, and 8) will drive the coin against the left end of the slide 58 so as to drive the slide 58 towards the right. As the slide 58 moves toward the right it assumes the 50 position shown in Fig. 7 so that the latch piece 41 slides out of the notch 39 of the spreader 29, and at about the same time or slightly thereafter, ejects the coin downward into the coin trap 71 where it stops against a pin 72 which extends into 55 the coin trap 71. In driving the coin down into the coin trap 71, the slide 58 executes a return motion towards the left under force of its spring 69. A fuller description of the mode of operation of the latch mechanism consisting of the 60 latch piece 41 and the spreader 23 of the snap mechanism will appear presently.

Depending from the coin trap 71 is a pivoted chute 75 which is adapted, when in the position in which it is shown in Fig. 3, to guide the coin 65 into position opposite an opening 76 in the panel 14 where it is supported on projections 78 and where it is exposed to the view of the player of the machine. The center of gravity of the chute 75 is so located that it naturally hangs open in 70 the position in which it is shown in Fig. 4. If desired a spring can be employed for holding the chute 75 away from the panel 14. In addition, the weight of a coin lying in the chute 75 in front of the opening 76 in the panel 14, also, will 75

tend to cause the chute 75 to swing open. In the open position in which it is shown in Fig. 4, the chute 75 is adapted to discharge the coin therefrom by dropping it into a coin box 79.

As best may be seen in Fig. 1, the shaft 21 carries an arm 82, which in turn carries a link 83 pivoted thereto. The link 83 is slotted and its slot engages a pin of a lever 84. The lever 84 is normally held up in the position in which it is shown in Fig. 1 by means of a spring 85. The lever 84 carries a cam 86 which is adapted to engage the lever 62 to drive it towards the left as viewed in Fig. 1 so as to drive the slide 57 in the manner already described. The cam 86, also, engages an arm 88 of the chute 75 so that the arm 84, when it is in its normal position as shown in Fig. 1 and as, also shown in Fig. 3, closes the chute 75. Secured to the panel 14 is a shaft 90 having an arm 91 which preferably is formed integrally therewith. The arm 91 is curved and depends from the shaft 90 so as to engage a roller 92 carried by the pin 30 of the arm 28 of the snap mechanism. A spring 93 tends to rotate the shaft 90 in a clockwise direction as viewed in Fig. 2 and in a counter-clockwise direction as viewed in Figs. 3, 4, and 5 so as to hold the arm 91 firmly in engagement with the roller 92. The curved portion of the arm 91 is so configured that the arm 91 is rotated against the force of the spring 93 in a counter-clockwise direction as viewed in Fig. 2 when the arm 28 moves from the position in which it is shown in Fig. 2 down into the position in which it stops against the boss 33 as shown in dotted lines in Fig. 5. A catch 96 carried by the arm 90 is adapted to engage the arm 62 so as to block its motion when the apparatus assumes the position in which it is shown in Fig. 5. This operation will be explained presently. The shaft 90, also, carries an arm 97 which in turn carries the pin 72. When the apparatus is in the position of Fig. 5, the pin 72 is withdrawn from the coin trap 71 so as to leave a passage therethrough unobstructed. The arm 97, also, engages an arm 98 of the coin trap 75 so as to hold the coin chute closed when the apparatus is in the position in which it is shown in Fig. 5.

The latch piece 41 has a small projection 101 thereon which is adapted under certain conditions to engage the spreader 29 and retain it in a position rotated counter-clockwise as viewed in Fig. 2 from the position in which it is shown in Fig. 2. As was previously pointed out, the arrangement of the fastening points of the springs 37 and 38 on the spreaders 23 and 29 is such as to cause the spreaders 23 and 29 always to tend to assume positions in which they lie substantially perpendicular to the line between the pins 24 and 30. Therefore, when the arm 22 carries the pin 24 down, the spreaders 23 and 29 tend to rotate counter-clockwise as viewed in Fig. 2 but this rotation is prevented by the engagement of the notch 39 of the spreader 29 with the end of the latch piece 41. Assume that the pin 24 moves downwards with the arm 22 but not far enough to cause a line between the pins 24 and 30 to cross the axis of the shaft 26, and that then the latch piece 41 slips out of the notch 39 of the spreader 29. The latch piece will leave the notch 39 by moving toward the right as seen in Figs. 6 and 7. As soon as the latch piece disengages the spreader 29 in this manner, the two spreaders 23 and 29 immediately rotate in a counter-clockwise direction as seen in Fig. 2 to assume positions substantially perpendicular to the line between the

pins 24 and 30, thereafter if the latch piece 41 again moves to the left as viewed in Figs. 6 and 7 the projection 101 of the latch piece 41 will project past the spreader 29 to the right thereof as viewed in Fig. 2, the body of the latch piece 41 stopping against the flat surface of spreader 29. Then, if the arm 22 is permitted to rise, the spreaders 23 and 29 will rotate in a clockwise direction as viewed in Fig. 2 until the right side of the spreader 29 as viewed in Fig. 2 engages the projection 101 of the latch piece 43 so as to prevent the spreader 29 from assuming a position such that the latch piece 41 could re-enter the notch 39. With the apparatus in this condition, the operation of the arm 28 is no longer latched or locked by the latch piece 41 and the snap mechanism may be operated to spin the wheel 10. Moving the arm 22 to its lowermost position causes the arm 28 to snap down to its lowermost position and in so doing to spin the wheel 10 in the manner already described.

When the arm 22 again is permitted to rise the spreaders 23 and 29 rotate so that they assume positions in which they extend upwards and towards the right in Fig. 2. In this condition, the arm 22 is in the position in which it is shown in Fig. 2 but the arm 28 is in its lower position stopping against the boss 33. As the arm 28 snaps up to its normal position, the spreader 29 tends to keep itself in a position perpendicular to the line through the pins 24 and 30 and in so doing rotates in a counter-clockwise direction. Assuming that the latch piece 41 lies in its normal position, with the slide 58 which carries it in its extreme left position as shown in Fig. 6, the left edge of the spreader 29 as viewed in Fig. 2 will strike against the end of the latch piece 41 and as the arm 28 stops against the boss 33, the notch 39 of the spreader 29 fits itself over the end of the latch piece 41 so as to return the apparatus to the condition in which it is shown in Fig. 2.

The operation of the complete apparatus is as follows: Assume that the apparatus is all in its normal condition with the various parts of the machine in the position in which they are shown in Figs. 1, 2, 3, 6, and 8. A coin may be inserted in the hollow of the casting 51 from which it will drop into the position in which it is shown in Fig. 6. Then the hand lever already mentioned (but not shown) may be actuated to rotate the shaft 21 in the counter-clockwise direction as viewed in Fig. 2. This moves both of the levers 22 and 82 downwards.

As the lever 82 moves downward, the link 83 takes up the slack provided by its slot and then actuates the lever 84. The cam 86 of the lever 84 moves away from the arm 88 of the chute 75 so as to open the same (permit it to fall away from the panel 14) and permit any coin therein to drop into the coin box 79. Continued motion of the lever 82 causes the lever 84 and its cam 86 to drive the lever 62 which in turn drives the slide 57. The slide 57 moves to the right as seen in Figs. 6, 7, and 8 and because of the presence of the coin, also drives the slide 58 toward the right to disengage the latch piece 41 from the slot 39 in the spreader 29 of the snap mechanism. Subsequently, or at about the same time, the coin comes into register with the opening between the channel containing the slides 57 and 58 and the coin trap 71 so that it is ejected into the trap 71 where it rests on the pin 72. During the entire motion of the shaft 21 and the lever 82, the lever 22 has been causing 38 to 75

lengthen, and the line of action of the springs (the line through the center of the pins 24 and 30) has been approaching the axis of shaft 26. Subsequent to the discharge of the coin into the trap 71 the line of action between the pins 24 and 30 crosses the axis of shaft 26 and the arm 28 of the snap mechanism snaps down to its lower position where it stops against the boss 34 and in so doing sets the wheel 10 into motion in the manner already described.

The arm 28 in moving to its lower position also has moved the arm 91 to the right as seen in Fig. 2 so as to perform the following operations:

15 (1) The catch 96 has been brought into position to block the lever 62 so as to prevent the return of the slide 57 to its normal position in which it could receive another coin.

20 (2) The arm 97 has withdrawn the pin 72 from the coin trap 71, and in so doing has engaged the arm 98 of the chute 75 to close the same. This has permitted the coin to drop into the chute 75 in position where it may be viewed easily in the opening 76.

25 The wheel 10 which has been set into motion by the snap mechanism spins freely and eventually comes to a random stop with the dog carried by the weights 43 and 44 seated in one of the notches of the notched wheel 45. This brings 30 one of the characters of the design on the periphery of the wheel 10 squarely into register with the index in the opening 12 to indicate the random selection of the machine. This takes place automatically regardless of whether or not 35 the player permits the handle to return to its normal position, and the stopping of the wheel 10 may take place either before or after the handle is permitted to return. As the player permits the handle to return to its normal position, 40 the lever 84 moves under force of its spring 85 back to its normal position so that the cam 86 engages the arm 88 of the chute 75 to hold it in its closed position. The catch 96 continues to hold the lever 62 and the slide 57 in their extreme right position as viewed in Figs. 6, 7, and 8 (extreme left position as viewed in Fig. 1). When 45 the handle has substantially completed its return motion, the line of action of the springs 37 and 38 between the pins 24 and 30 again crosses the axis of the shaft 26 so that the arm 28 snaps back to its normal or upper position where it 50 stops against the boss 34. In so doing it permits the arm 91 to return to its normal position in which it is shown in Fig. 1. This rotates the shaft 98 to accomplish the following:

55 (1) The catch 96 releases the arm 62 so that the slide 57 snaps back under the force of its spring 62 to its normal position in which it is shown in Figs. 6 and 8.

60 (2) The arm 97 moves the pin 72 into the coin trap 91. While the arm 97 moves away from the arm 98 of the chute 75, the chute does not open because it is held by the cam 86 of the arm 84.

65 The action of the arm 28 of the snap mechanism in snapping to its normal or upper position (in which it is shown in Fig. 2) does not rotate the wheel 10 because the overrunning clutch 27 does not permit the arm 28 to drive the wheel in a counter-clockwise direction as viewed in Fig. 2. The handle now may be operated through a considerable portion of its stroke so as to actuate the lever 84 so that the cam 86 releases the arm 98 to open the chute 75 and drop the coin from its position behind the opening 76 in the panel 70 14 into the coin box 79. This operation of the

75 handle does not cause the wheel to spin because since no coin has been inserted into the space between the end of the slide 58 and the projection 65 on the slide 57, the latch piece 41 will continue to engage the notch 59 in the spreader 29 so as to prevent the operation of the arm 28 in the manner already described.

80 It thus is seen that we have provided a simple mechanism for detecting coins for the purpose of controlling the operation of machines of the class described, which mechanism so controls and handles the coin itself as to accomplish the following: First, it prevents operation of the machine when no coin is inserted therein; second, it permits operation of the machine in response 15 to the insertion of each coin regardless of the manner in which the player may manipulate the operating handle; third, it takes each coin and exhibits it to view in response to that particular 20 operation of the machine which that particular coin has controlled; fourth, it prevents coins from being inserted and moved to the exhibiting position without causing an operation of the machine with the admission of each coin; and fifth, it permits the coins to be removed from the exhibiting position without further operation of the machine.

25 While the machine described herein may be manipulated under certain conditions so as to introduce a number of coins into the coin trap 71, 30 at one time, no coin can be passed therefrom to the chute 75 where it is held in exhibiting position behind the opening 76 without producing an operation of the wheel 10. In fact it is the 35 operation itself of the wheel 10 which controls the transfer of the coin from the trap 71 to the chute 75.

40 It is to be further observed that it is virtually impossible for coins to jam in the coin detecting and handling mechanism because the coins continually are conducted into larger and larger spaces. Thus for example, if a player should insert a coin into the position in which it is shown in Fig. 6 and then should operate the handle, (not shown), sufficiently to transfer the coin into 45 the coin trap 71 where it rests on the pin 72, the latch piece 41 will disengage the notch 39 of the spreader 29 so as to leave the snap mechanism free to operate. Assume that under this condition, the arm 22 (shown in Fig. 2) has not moved 50 down sufficiently far to cause operation of the follower arm 28 of the snap mechanism. Now if the handle is released, the arm 22 will return to the position in which it is shown in Fig. 2 and the slide 57 will return to its normal position in which 55 it is shown in Fig. 6. Incidentally, the slide 58 will not return all the way to its normal position because the edge of the latch piece 41 (the right edge as seen in Fig. 1) will stop against the flat surface of the spreader 29 (the left side as seen 60 in Fig. 1), so that the projection 101 of the latch piece 41 will prevent the spreader 29 from assuming its erect position, (as seen in Fig. 2) all as previously has been described.

65 Inasmuch as the slide 57 has returned to its normal position, the projection 65 will have moved out from under the opening 52 to admit another coin. Now if the handle again is operated a distance just sufficient to introduce the second coin into the coin trap 71, the handle may 70 be returned again to its normal position so as to leave the two coins in the coin trap 71 resting on the pin 72. This can continue until the trap 71 is filled and will admit no more coins. Thereafter operation of the slide 57 with a coin in place in 75

the position in which it is shown in Fig. 6, will merely cause the slide 58 to move slightly farther to the right than it would if the coin were free to enter the trap 71. It is thus seen that when the trap 71 becomes full it merely prevents any further coins from being ejected from the channel containing the slides 57 and 58 with the result that the space between the slides will fill and will prevent further introduction of coins into the apparatus.

Now if the operating handle is actuated throughout its full travel, the arm 28 (see Fig. 2), will snap down to spin the wheel 10 and to actuate the arm 91 so as to withdraw the pin 72 from the coin trap 71. This permits the coins to drop into the chute 75, the chute 75 being in the position in which it is shown in Fig. 5. Under this condition, the chute presents a tapered passage for the coins and they may not empty the trap 71 completely. They may even jam where the passageway bends and tapers down so as to prevent any coin from coming into position behind the window 76. This congestion at this point does no harm and it will clear itself after the hand lever is released or in response to further operation of the machine. When the handle is released, the apparatus returns to its normal position in the manner already described without actuating the chute 75. The handle now may be operated to open the chute 75 and any coins which are not caught between the pin 72 and the panel 14 will drop immediately into the coin box 79. Any coins which may happen to be caught between the pin 72 and the panel 14 will be gripped only by the pressure of the spring 93. The arm 97 is substantially nonresilient and therefore a slight jar of the apparatus, will cause the pin 72 to slightly release its grip of the coins so caught. Repeated jars such as those produced by striking the case 35 with the hand or by operating the machine, will permit the coins to creep down and escape into the chute 75 from which they may be discharged into the coin pan. If the congestion in the coin trap 71 has caused any coins to be left 45 in the space between the slides 57 and 58 their presence there will permit the apparatus to be actuated again in the normal manner.

If no attempt is made to remove coins from the coin trap 71 which may have caught between the end of the pin 72 and the panel 14, these will be given an opportunity to escape at the next operation of the follower arm 28 of the snap mechanism. The machine may not clear itself in one operation of the handle but it will always clear any congestion after several repeated operations.

It is to be observed that when the coin chute 75 is permitted to open by swinging away from the panel 14, it swings back to entirely clear the lower opening of the coin trap 71. The drawings do not illustrate chute 75 in its fully open position. Fig. 4 shows it in the position which it assumes when hanging free. The weight of one or more coins will move it farther open. Therefore, unless the coin chute 75 is held against the panel either by the cam 86 or the arm 97 it cannot obstruct the discharge of coins from the coin trap 71.

Obviously, if a congestion occurs in the coin trap 71, as for example, the coins being caught between the pin 72 of the panel 14, without leaving any coin in the channel between the slides 57 and 58, it will be necessary to insert an additional coin in order that the slide 58 may oper-

ate the latch piece 41 to release the snap mechanism.

Referring now to the latch and snap mechanisms shown in Figure 2, it is not necessary to employ both spreaders 23 and 29 to produce the desired latching action between the latch piece 41 and the spreader 29. It is necessary only that the linkage be so arranged that the spreader 29 always tends to assume a position which is substantially perpendicular to the line between the pins 24 and 30. Thus, so far as the operation of the latching mechanism is concerned, spreader 23 could be eliminated and the springs 37 and 38 attached directly to the pin 24.

While we have shown and described a single specific embodiment of our present invention, it will be apparent to those skilled in the art that the same is by way of illustration only, and that the invention is capable of numerous modifications and variations. Therefore, we do not wish to be limited except by the scope of the appended claims.

We claim:

1. In combination in a device of the class described, means defining a conduit for a coin, said conduit having an entrance opening therein for admitting said coin and having an exit opening therein for permitting the exit of said coin, a coin driving member in said conduit adapted to propel a coin therethrough, a coin driven member in said conduit adapted to be driven by a coin propelled by said coin driving member, said exit opening being normally obstructed by said coin driven member, said coin driven member being adapted to un-cover said exit opening in response to being driven by the coin, a handle for operating said coin driving member, a wheel adapted to be rotated, mechanism for driving said wheel, a resilient driving connection between said handle and said mechanism, a latch member carried by said coin driven member and engaging said mechanism so as to prevent an actuation thereof, said latch being adapted to be moved to release the driving means of said wheel when said coin driven member is driven by a coin.

2. In combination in an apparatus of the class described, means defining a channel having an entrance aperture therein for the entrance of a coin and an exit aperture off-set in the longitudinal direction of said channel from the entrance aperture for the exit of said coin, a coin driving slide in said channel adapted to propel a coin through said channel from a position opposite the entrance aperture to a position opposite the exit aperture, a coin driven slide in said channel, means including a spring for defining a normal position of said coin driven slide such that said coin driven slide normally obstructs said exit aperture, said coin driven slide being adapted to be driven by a coin propelled by said coin driving slide so as to un-cover said exit aperture, the driving and driven surfaces respectively of said slides being converging so that the resultant of their opposing forces directed against the coin in the channel urges the coin through said exit aperture, a rotatable wheel, means for driving said wheel including a snap mechanism which comprises a pivoted actuator arm, a pivoted follower arm and a spring connected between said arms, a single handle for operating both said coin driving slide and the actuator arm of said snap mechanism, a latch for normally restraining said follower arm to prevent operation of said snap mechanism, and means inter-connecting said coin driven member and said latch for caus-

ing said coin driven member when propelled by a coin to disengage said latch.

3. In combination in a device of the class described, the coin conduit, coin controlled mechanism therein, a rotatable wheel, a snap mechanism for driving said wheel, said snap mechanism comprising an actuator arm, a follower arm and a spring connected between said arms, a latch for restraining the motion of said follower arm so as to prevent operation of said snap mechanism, a handle for operating said actuator arm and means operated by said handle under control of said coin controlled mechanism for releasing said latch.

15 4. In combination in a device of the class described, a wheel adapted to be rotated, a snap actuator arm, a snap follower arm, means connecting said follower arm and said wheel adapted to transmit torque from said follower arm to said 20 wheel for only one direction of rotation of said follower arm, spring connections between said snap actuator arm and said follower arm, said connections including a first latch piece pivoted to said follower arm and adapted to tend to assume a fixed orientation with respect to a line 25 through the points of fastening of said spring connections to said actuator and follower arms respectively and a second latch piece adapted to engage said first latch piece to prevent operation 30 of said follower arm.

5. In combination in a device of the class described, a rotatable wheel, a snap mechanism comprising an actuator arm, a follower arm and spring means connected between said arms, driving means connecting said follower arm to said wheel, said driving means being adapted to drive said wheel from said follower arm in response to only one direction of rotation of said follower arm, said actuator and follower arms having 40 spring fastening points thereon, said spring means comprising a spreader pivoted to said follower arm at the spring fastening point thereof and comprising also springs connected between said spreader and the spring fastening point of 45 said actuator arm, said springs being adapted to tend to hold said spreader in a fixed orientation with respect to a line extending through the spring fastening points of said actuator and follower arms, said spreader having a latch portion disposed approximately on a line running 50 from said spring fastening point of the follower arm perpendicular to the line through the two spring fastening points and lying substantially in the plane of the arcuate motion of said follower 55 arm, said latch portion of said spreader lying also in a direction from the spring fastening point of said follower which is opposite to the direction in which said spring fastening point moves out of its normal position, and a latch 60 piece adapted to be engaged by said latch portion of said spreader when said follower arm lies in its normal position.

6. In combination in an apparatus of the class described, a coin conduit, coin controlled means therein, a coin trap adapted to receive a coin from said coin controlled means, said coin trap providing two positions in which to hold the coin, a wheel adapted to be rotated, means for rotating said wheel comprising an actuator arm, a follower arm and spring connections between said arms, a latch for holding said follower arm and adapted to be released by said coin controlled means in response to an actuation of said actuating arm when a coin is in said conduit, said coin 75 controlled means being adapted to deliver said

coin to the first position of said coin trap substantially simultaneously with the release of said latch, and means responsive to the operation of said follower arm for causing a coin to move from the first to the second position of said coin trap. 5

7. In combination in an apparatus of the class described, a handle having a normal position, coin controlled means adapted to receive a coin, a coin trap adapted to receive a coin from said coin controlled means, said coin trap providing two 10 positions in which to hold the coin, first means for retaining a coin in the first position in said trap, second means for holding a coin in the second position of said trap, a wheel adapted to be rotated, means for rotating said wheel comprising 15 an actuator arm operated by an actuation of said handle, and comprising also a follower arm and spring connections between said arms, a latch for holding said follower arm and adapted to release the same under control of said coin controlled means in response to an actuation of said handle as aforesaid when a coin is in said coin controlled means, said coin controlled means being adapted to deliver a coin to the first position of said coin trap substantially simultaneously with the release of said latch, means actuated 20 by an operation of said follower arm for substantially simultaneously withdrawing said first means from coin holding position and moving said second means into coin holding position, and means 25 operated by said handle for moving said second means into coin holding position in response to the return of said handle to its normal position.

8. In combination in an apparatus of the class described, a coin conduit having an entrance 35 aperture therein for admitting a coin and having an exit aperture therein for permitting the exit of a coin, said exit aperture being offset from said entrance aperture in the longitudinal direction of said conduit, a coin driving slide in 40 said conduit adapted to propel a coin through said conduit from a position opposite said entrance aperture to a position opposite said exit aperture and in so doing to move itself into position to obstruct said entrance aperture, means 45 including a spring for defining a normal position of said coin driving slide such that said entrance aperture is unobstructed, a coin driven slide in said conduit, adapted to be driven by a coin propelled by said coin driving slide, means including 50 a spring for defining a normal position of said coin driven slide, said coin driven slide being adapted to obstruct said exit opening when in its normal position and to move out of said normal position to uncover said exit aperture when driven 55 by a coin, said slides being adapted to eject a coin from said conduit through said exit aperture, a rotatable wheel, an actuator arm having a spring fastening point, a follower arm having a spring fastening point, means for driving said 60 follower arm from said actuator arm and for defining normal positions of said actuator and follower arms including spring means acting between said spring fastening points, said spring means including a spring and a member adapted 65 to tend to assume a fixed orientation with respect to a straight line through said spring fastening points, a latch engaging said member for retaining said follower arm in its normal position, said latch being adapted to be disengaged by said 70 coin driven member when said coin driven member is driven by a coin out of its normal position, driving means adapted to rotate said wheel when said follower arm moves out of its normal position, a coin trap adapted to receive a coin 75

from said conduit and to hold it in a first coin holding position and to transfer it therefrom to a second coin holding position, first coin holding means for normally holding a coin in said first coin holding position and adapted to release it therefrom when said follower arm moves out of its normal position, a handle for operating said actuator arm and said coin driving slide, second coin holding means adapted to hold a coin in

said second coin holding position when said actuator arm is in its normal position and also when said follower arm is out of its normal position a latch for catching and holding said coin driving slide in position to obstruct the entrance aperture of said conduit when said follower arm is out of its normal position.
